(57) **CLAIM**

What is claimed is the ornamental Design for a reclosable container lid, as shown and described.

DESCRIPTION

FIG. 1 is a perspective view of a reclosable container lid of the invention, showing the Lid in a closed position;

FIG. 2 is a side view of the reclosable container lid of FIG. 1;

FIG. 3 is a side view of the reclosable container lid of FIG. 1;

FIG. 4 is a side view of the reclosable container lid of FIG. 1;

FIG. 5 is a top view of the reclosable container lid of FIG. 1;

FIG. 6 is a perspective view of the reclosable container lid of FIG. 1, showing the Lid in an open position; and,

FIG. 7 is a sectional view of the reclosable container lid taken along line 7—7 of FIG. 1, showing the contour of the Lid.
